UNITED STATES PATENT OFFICE.

WILLIAM L. MORROW, OF STOCKTON, CALIFORNIA.

TANDEM STEAM-ENGINE.

No. 833,475.

Specification of Letters Patent.

Patented Oct. 16, 1906.

Application filed November 9, 1905. Serial No. 286,512.

To all whom it may concern:

Be it known that I, WILLIAM L. MORROW, a citizen of the United States, and a resident of Stockton, county of San Joaquin, and State of California, have invented certain new and useful Improvements in Tandem Steam-Engines; and I do declare the following to be a full, clear, and exact description of the invention, such as will enable others skilled in the art to which it appertains to make and use the same, reference being had to the accompanying drawings, and the characters of reference marked thereon, which form a part of this specification.

This invention relates to improvements in engines; and my object is to produce a double two-cycle steam-engine by the use of which more power may be produced than is now the case. This object I accomplish by a cylinder having a division-wall dividing said cylinder into two chambers and by such other construction as will appear from the following specification and claims.

In the drawings similar characters of reference indicate corresponding parts in all the views.

Figure 1 is a sectional view of the device. Fig. 2 is a side elevation of the same. Fig. 3 is a sectional view on a line $x-x$ of Fig. 2.

1 designates the cylinder, provided with a division-wall 2, which divides said cylinder into two chambers 3 and 4. At each end of said cylinder and at both sides are slots 5, lying parallel to each other, and 6 represents similar slots in the top of said cylinder.

7 is a piston working in the chamber 3, and 8 is a similar piston working in the chamber 4 in a direction similar to the piston 7.

9 is an oblong driving-rod connected to the pistons 7 and 8 and extending through the slots 5 and along the sides of the cylinder 1. 10 represents guides arranged on the cylinder 1 to regulate the movement of the driving-rod 9.

11 represents exhaust-ports in the chambers 3 and 4.

12 is a shaft journaled beneath the cylinder 1 about the center thereof, on the ends of which are secured cog-wheels 13 and 14, said cog-wheels being provided with cogs on one side only, those on one being disposed opposite to those on the other.

15 and 16 are cog-rails on each side of the cylinder 1, secured to the driving-rod 9, the cogs on said rods coacting with the cogs on the wheels 13 and 14, those on the rail 15 running

over the wheel 13, and those on the rail 16 running under the wheel 14. To the shaft 12 is secured the fly-wheels 17, suitably connected to the cog-wheels 13 and 14.

On the top of the cylinder 1 is secured a slide-valve seat 18, in which operates a valve-slide 19. On the top of the valve-seat 18 is a steam-chest 20, from which orifices 21 and 22 lead to the chambers 3 and 4, respectively. The slide 19 is secured to the driving-rod 9 by rods 23, said rods working in the slots 6. In the slide 19 is an orifice 24, which coincides with the orifice 21 when the piston 7 is in its inner position, and 25 is a similar orifice which coincides with the orifice 22 when the piston 8 is in its inner position.

The operation is as follows: The steam passes through the orifices 21 and 24 into the chamber 3 and expands and drives the piston 7 backward, which action pulls the piston 8 inward and causes the orifice 25 to coincide with the orifice 22, and then the steam exhausts from the chamber 3, and new steam passes into the chamber 4 and expands and drives the piston 8 outward, pulling the piston 7 and its parts inward, &c. The cog-wheel arrangement 13 14 15 16 drives the fly-wheels 17, since the wheels 13 and 14 are provided with cogs on only one side, those on one being disposed oppositely to those on the other, and with one drive of the pistons the rail 16 engages with the cogs on the wheel 14 and revolves the shaft 12, which action brings the cogs on the wheel 13 into connection with the cogs on the rails 15, and then the pistons reciprocate and the rail 15 performs a like action as the rail 16, thus giving continuous rotary motion to the fly-wheels. I have thus produced a double-cycle engine for steam which will produce more power than the old-style engines.

I have now entered into a detailed description of the present and preferred embodiment of my invention. I do not desire, however, to be understood as confining myself to such specific detail, as such changes and modifications may be made in practice as fairly fall within the scope of my claims.

I claim as new and useful and desire to secure by Letters Patent—

1. In an engine a cylinder provided with a division-wall dividing said cylinder into two chambers, a piston working in each chamber said pistons being connected by an oblong driving-rod extending through and along the sides of said cylinder, slots in the top of said

cylinder at both ends, a slide-valve arranged above said cylinder with rods connecting the valve-rod to said driving-rod and working in said slots, and a steam-chest arranged above said slide-valve, said valve admitting steam alternately into each of said chambers, as set forth.

2. In an engine a cylinder provided with a division-wall dividing said cylinder into two chambers, a piston working in each chamber, an oblong driving-rod connected to said pistons and extending through and along the sides of said cylinders, a shaft journaled beneath said cylinder about the center thereof, cog-wheels arranged on each end of said

shaft said wheels being provided with cogs on but one side thereof, those on one wheel being disposed opposite to those on the other, cog-rails attached to said driving-rod, one of said rails coacting with the under side of one of said cog-wheels and the other with the upper side of the other cog-wheel, as set forth fully ²⁰ herein.

In testimony whereof I affix my signature in presence of two witnesses.

WILLIAM L. MORROW.
